UNITED STATES PATENT OFFICE.

HARLAN A. HADLEY, OF ST. JOHNSBURY, VERMONT, ASSIGNOR TO E. AND T. FAIRBANKS AND COMPANY, OF ST. JOHNSBURY, VERMONT, A CORPORATION OF VERMONT.

DESIGN FOR A SCALE CASING.

Application filed April 30, 1927. Serial No. 21,810. Term of patent 14 years.

To all whom it may concern:

Be it known that I, HARLAN A. HADLEY, a citizen of the United States of America, residing at St. Johnsbury, in the county of Caledonia and State of Vermont, have invented a new, original, and ornamental Design for a Scale Casing, of which the following is a specification, reference being had to the accompanying drawings, forming part thereof, and in which—

Figure 1 is a plan; and

Figure 2 an edge view of a scale casing, showing my new design.

I claim:

The ornamental design for a scale casing, as shown.

HARLAN A. HADLEY.
